CLAIM

The ornamental design for wireless signal transmitter box, as shown.

DESCRIPTION

FIG. 1 is a perspective view of a wireless signal transmitter box;

FIG. 2 is a rear elevational view of the wireless signal transmitter box;

FIG. 3 is a first side elevational view of the wireless signal transmitter box;

FIG. 4 is a front elevational view of the wireless signal transmitter box;

FIG. 5 is a second side elevational view of the wireless signal transmitter box;

FIG. 6 is a top plan view of the wireless signal transmitter box; and,

FIG. 7 is a bottom plan view of the wireless signal transmitter box.

The broken lines included in the drawings represent environment only and form no part claim of the claimed design.
